HIGHCHAIR

Oliver J. Calder, Wilmington, Calif.

Application April 6, 1956, Serial No. 40,956

Term of patent 14 years

(Cl. D15—1)

FIG. 1.

12

FIG. 2.

3

FIG. 3.

Fig. 1 is a perspective view of a highchair showing my new design;

Fig. 2 is an elevational view of the highchair in elevated position, taken in the direction of the arrow 2 of Fig. 1; and

Fig. 3 is an elevational view of the highchair shown in Fig. 2, taken in the direction of the arrow 3 of Fig. 2.

I claim:

The ornamental design for a highchair, as shown.
